HOSE SUPPORTING GARMENT

Jeanne Monette, Montreal, Quebec, Canada, assignor of one-half to Pierre Charton, Montreal, Quebec, Canada

Application January 24, 1935, Serial No. 3,302

2 Claims. (Cl. 2—70)

The present invention relates to hose supporting garments.

An important object of the invention is the provision of a hose supporting garment which will 5 preserve and substantially prolong the life of women's hose.

Another object of the invention is the provision of a hose supporting garment designed so that the supporting tension will be distributed circumferentially about the hose so as to obviate widely separated strain.

A further object of the invention is the provision of a hose supporting garment which will obviate the formation of objectionable protuberances.

Still another object of the invention is the provision of a hose supporting garment of the aforesaid character which will maintain the hose in smooth proper fitting position.

20 Another object of the invention is the provision of hose supporting means of the above character which will enable retention of the hose seams in proper, neatly appearing arrangement.

25 Another object of the invention is the provision of a hose supporting garment which will effectively replace and obviate the necessity of wearing a separate bloomer garment.

A still further object of the invention is the provision of hose supporting means of the above 30 character which may be quickly and conveniently put on or removed and which will be comfortable on the person.

Other objects and advantages of the invention will become apparent as the description 35 progresses.

In the accompanying drawings forming a part of this specification and in which like reference characters are employed to designate corresponding parts throughout the same:

40 Figure 1 is a perspective view showing the preferred form of garment in dress position,

Figure 2 is a front elevational view of the garment,

45 Figure 3 is an enlarged fragmentary section taken on the line 3—3 of Figure 2,

Figure 4 is a front elevation showing the garment in separated position,

Figure 5 is a transverse section taken on the line 5—5 of Figure 4,

50 Figure 6 is a similar view showing the garment in open arrangement,

Figure 7 is a perspective view showing the garment in partially detached position.

55 Figure 8 is a similar view showing the garment in almost completely detached position,

Figure 9 is a front elevational view showing a modified form of the garment.

Figure 10 is a similar fragmentary view showing the parts in separated position,

Figure 11 is an enlarged section taken on the line 11—11 of Figure 9,

Figure 12 is a fragmentary perspective showing the connection of the hose with the garment,

Figure 13 is a fragmentary perspective showing the construction of the hose top,

Figure 14 is an enlarged fragmentary section taken on the line 14—14 of Figure 9,

Figure 15 is a fragmentary front elevation showing still another modified form of the garment, and

Figure 16 is a fragmentary perspective view of the same.

Referring to Figures 1 to 8 inclusive, wherein is illustrated a preferred embodiment of the invention, the numeral 20 designates a hose supporting garment preferably constituting a relatively short leg garment adapted to fitted about the thighs and hips of a wearer. I consider it advantageous that the leg garment 20 be formed of suitable elastic material. This garment is also preferably constructed to provide a doubled overlapping crotch portion 21 which may be easily opened when necessary, as shown at Figure 6.

The leg garment 20 may be supported on the body by detachably connecting the same with an upper body garment 22 which may be a foundation garment, such as a corset or close fitting elastic waist garment.

At the lower edge of the upper body garment 22 and the upper edge of the lower leg garment 20 are preferably provided slider fastening means of any preferred type, such as a fastener embodying interlocking elements 24 interlocked or separated by movement of a slider 25. This connection is such that by moving the slider circumferentially, the upper and lower garments may be connected in intimate edge to edge relation or entirely detached.

To the lower leg portions of the hose supporting garment 20 are connected a pair of hose 26, in the present instance having the top or upper marginal edge portion disposed in overlapping position with respect to the leg portions of the garment and secured thereto by a circumferential row of stitching 27. This stitching securely attaches the hose to the leg garment so as to form an integral structure therewith.

Referring to Figures 9 to 14 inclusive wherein is illustrated a modified form of the garment, the leg garment indicated at 29 is also attached by

a sliding fastener 30 to an upper body garment 31. The bottom leg portions of the garment 29 differ, however, in that they are provided at circumferentially spaced intervals with slits or holes 32. For this garment, the hose indicated at 34 would have the edge margin of the tops also formed with slits 35 which would be adapted to register approximately with the slits 32 in the leg garment.

To attach the hose to the supporting garment, the tops of the hose are arranged in overlapping position over the margins of the legs and a flexible band 36, which may also be elastic, is threaded or laced through the registering slits in the hose and garment. When the band has been completely laced the ends are secured by hooks and eyes or other suitable fastening means.

In still another modified form of the invention shown at Figures 15 and 16 the garment supporter, indicated at 38, is identical with that employed in the modified form shown at Figure 9 but the hose are modified in that a lining band 39 is connected to the top margin of the hose, indicated at 40, by stitching or the like and projects beyond the top edge of the hose. The lining band 39 is preferably formed of durable flexible material and is provided, at spaced intervals, with slits 41 which are adapted to register with the slits in the legs of the supporting garment to receive the flexible fastening band.

As will be readily apparent the leg garment and the hose may be quickly and easily put on or removed as a single unit although, when necessary, the hose may be detached and changed.

Due to the connection of the hose with the leg garment at closely disposed circumferentially spaced points, a very desirable supporting connection is provided, inasmuch as the hose are held in a smooth tight fitting arrangement and the uniform distribution of tension obviates injury to the stocking, which frequently results from the strain caused by widely separated two or three point connections afforded by the commonly used garter.

It is to be understood that the forms of my invention herein shown and described are to be taken as preferred examples of the same, and that various changes as to the shape, size and arrangement of parts may be resorted to without departing from the spirit of the invention or the scope of the subjoined claims.

Having thus described my invention, I claim:—

1. In an undergarment having trunk and seat portions, the combination therewith of a narrow crotch portion having lower thigh openings, means for uninterruptedly connecting said last portion to the lower edge of the seat portion in a removable manner, full-length hose, and co-operating means on the marginal edge of the 25 thigh openings and upper part of the hose for removably securing said hose to said crotch at closely spaced points around its periphery.
2. In a lady's undergarment as claimed in claim 1, an elastic band secured to the hose at 30 the connecting point with the crotch, for the purpose of reinforcing said hose which is usually of thin easily tearable material.

JEANNE MONETTE.
